SCRAPING AND CUTTING TOOL

Frank B. Williams, Chicago, Ill.

Application December 19, 1938, Serial No. 246,572

3 Claims. (Cl. 30—321)

This invention relates to improvements in a scraping and cutting tool adapted to utilize safety razor and like blades, and which is adjustable to various positions so that it can be used for a multiple of tasks, and is a continuation-in-part of my co-pending application Serial No. 97,529, filed August 24, 1936.

One of the objects of this invention is to provide an improved blade clamping portion or unit which will firmly hold a blade through hard usage, such as when used for scraping, cutting, and the like purposes.

Another object is to provide an improved blade clamping portion which will firmly hold the blade and which can be adjusted to a number of positions or angles or to a guarded position, as a single unit.

Another object relates to a method of adjusting and securing the blade clamp in various positions or angles on the handle portion of the tool.

Other objects relate to various features of construction and arrangement of parts which will be apparent from consideration of the following specification and accompanying drawing, wherein:

Fig. 1 is a rear elevation of my device.

Fig. 2 is a front elevation thereof, showing the blade clamping unit set at various angles, of my preferred form.

Fig. 3 is a side view of the form of device shown in Fig. 2.

Fig. 4 is a longitudinal section through the blade clamping unit, enlarged for clearness of illustration.

Fig. 5 is a side view similar to that shown in Fig. 3, illustrating a modified form of blade clamping unit construction.

Fig. 6 is a longitudinal section through the blade clamping unit shown in Fig. 5, enlarged for clearness of illustration.

Fig. 7 is a detail in perspective of the blade clamping members shown in Figs. 2, 3 and 4.

Fig. 8 is a detail in perspective of the blade clamping unit shown in Figs. 5 and 6.

Referring to the drawing, 10 indicates the holder handle having a head portion 11 which may be offset rearwardly as shown, and is substantially of the width of a conventional razor blade. The handle portion illustrated, is provided with a flange extending at right angles thereto to form the side walls 12 terminating in inwardly extending longitudinal flanges 13 to provide a magazine or elongated chamber where extra blades may be kept such as razor blade 14

or the screw driver 14', or other like blades such as a putty knife blade, etc. A spring 15 preferably in the form shown such as a U-shaped member formed with bowed legs, seats under the flanges 13 and holds the extra blades in place regardless of their number, limited by the depth of the formed chamber. Thus an extra supply of blades is always on hand and ready for use when fragile blades such as razor blades become worn and broken, or the chamber may be used for storing convenient extra tools such as screw driver tips, putty knife blades and the like, all of which may be readily withdrawn from the chamber by merely inserting a finger between the opening formed by the opposed flanges.

Referring to Figs. 1, 2, 3, 4 and 7, the blade clamp unit consists of the plates 17 provided with apertures 18 adjacent the forward edge thereof, and is provided with the further substantially centrally located aperture 19, comprising one member of the clamping unit, and the plate 20, which comprises the second complementary member of the clamping unit is provided with a pair of projections 21 struck therefrom adjacent its forward edge. While these projections 21 are shown in the form of annular collars, it will be readily understood that they may be in the form of solid studs, and are formed so that they will extend into and register with the apertures 18 in the plate 17. The plate 20 is substantially of the same general configuration as the plate 17 and is additionally formed with the hexagonal portion 22 struck up from it and centrally of which is a threaded recess 23 in register with the recess 19. A screw 24 extends through the recesses 19 and 23 to hold the plates together in relative engagement as a unit by means of which a blade such as the razor blade 25 may be clamped between them as shown in detail in Fig. 4, interlocking engagement being obtained with a conventional razor blade by means of the projections 21 extending through the conventional perforations 29 of razor blades, or lateral indentations 29' provided on blade tools 45 which are not necessarily razor blades. The plate 20 may have formations struck inwardly therefrom such as 26 at its rearward edge opposed to the blade clamping edge to provide studs on its under surface such as at 27. It will also be readily understood that these studs may likewise be formed on plate 17 at the like edge so that it will extend between the two plates when placed in registry. These studs in addition to compensating for the thickness of the blade being clamped act as a wedge to force the

clamped members together at the blade clamping edges to more securely grip the blade. Thus when the screw 24 is extended through the aperture 19 of plate 17 and threaded through the aperture 23 of plate 20 and a blade placed between the plates, the screw 24 may be tightened so as to securely grip the blade at the forward edges of the opposed clamping members and aided by the wedging action of the studs 27 extending between the plates at the rearward edges.

The modified form of construction of the blade clamping unit shown in Figs. 6, 7 and 8 comprises the clamping plate members 17' and 20', the plate 17' being provided with projections 21' adapted to register with and extend into the apertures 18' to form engagement for a blade such as 25' clamped between them, and in a manner similar to my preferred form of construction. Likewise the clamping plate member 20' is provided with the hexagonal projection 22' extending upwardly from its surface and is provided with a central threaded aperture 23' in which may be fixedly positioned the screw 31. To maintain the plates 17' and 20' in relative engagement with each other plate 20' is provided at its lateral edges a pair of opposed apertured lugs 32 bent inwardly at right angles in which are pivotally engaged the lateral projections 33 extending from the plate 17'. The plate 17' is further provided with the headed screw 34 extending through a threaded opening in the rearward edge thereof and abuts against the rearward edge of plate 20'. The extension of this screw between the plates 17' and 20' in addition to compensating for the thickness of the blade 25' clamped between them acts as a wedge to force the plate clamping members together at the blade clamping edge to hold securely and grip the blade and at the same time also serves to form a firm locking engagement for the clamping unit which is adjustable for clamping action and blade thickness.

Struck up from the holder head 11 of the handle 10 is the hexagonal seat 28 centrally of which there is an opening adapted to receive through the screw 24 or the screw 31, the seat 28 being complementary to and adapted to receive the raised hexagonal portions 22 or 22' of the respective blade clamping units. A thumb nut 30 engages the screw 24 or the screw 31, and after the hexagonal projection of the blade clamping unit is set in any one of six positions in seat 28 the thumb nut is turned down to hold the blade clamping unit in the desired position for angular relationship to the handle. Thus Fig. 2 which may be illustrative of the operation of both forms of my blade clamping units, illustrates the blade set in three positions. The full lines indicating the blade edge at right angles to the axis of the handle for use in normal scraping operations and the like. One of the dotted line positions shows the blade edge parallel to the axis of the handle at which it may be best adapted for cutting and the third position indicates the blade edge nested against the widened portion of the head 11 so that the blade edge is guarded when not in use.

While I have shown the preferred forms of my construction, it will readily be apparent to one skilled in the art that various details may be re-

arranged and changes made within the scope of my invention without departing from the spirit thereof and I do not therefore wish to be restricted thereto except as limited by the following claims.

I claim as my invention:

1. A device of the class described comprising a handle portion and a blade clamping unit adapted to be engaged therewith in varied fixed angular relationship, the said blade clamping unit comprising a member having projections adjacent one edge adapted to position a blade, a second complementary member having apertures adjacent one edge adapted to receive the projections from said first member, means for holding said members in independent fixed relative engagement with each other as a unit, and means extending between said members adjacent to the edge opposed to the blade clamping edge to hold said members spaced apart at their rearward edges and to increase the clamping action at their forward edges and a hexagonal projection extending from the outer face of one of said members, the said handle comprising a head portion formed with a complementary hexagonal depression adapted to cooperate and seat with said projection, and means for holding said blade clamping unit releasably locked to said handle head portion in varied angular relationship to the said handle and in the plane thereof.

2. A device of the class described comprising a handle portion and a separable blade clamping unit adapted to be engaged therewith in varied fixed angular relationship, the said blade clamping unit comprising a member having projections adjacent one edge adapted to position a blade, a second complementary member having apertures adjacent one edge adapted to receive the projections from said first member, means for holding said members in independent fixed relative engagement with each other as a unit, means extending between said members adjacent to the edge opposed to the blade clamping edge to hold said members spaced apart at their rearward edges and to increase the clamping action at their forward edges, and an equiangular polygonal projection extending from the outer face of one of said members, the said handle comprising a head portion formed with a registering equiangular polygonal depression adapted to seat and cooperate with said projection, and means for holding said blade clamping unit releasably locked to said handle head portion in varied angular relationship to said handle.

3. In a device of the class described, a blade clamping unit comprising a member having projections adjacent one edge adapted to engage and position a blade and having a central aperture adapted to receive a screw, a second complementary member having apertures adjacent one edge adapted to receive the projections from said first member and having a central threaded aperture adapted to receive said screw and to draw the members together to hold the blade between them in fixed unitary relationship, and fixed projections extending from an inner face of and between said members adjacent the edge opposed to the blade clamping edge.

FRANK B. WILLIAMS.
